CLAIM

I claim the ornamental design for a swing along pivoting bird feeder, as shown and described.

DESCRIPTION

FIG. 1 is an isometric view of a swing along pivoting bird feeder showing my new design;

FIG. 2 is a front elevational view thereof;

FIG. 3 is a top plan view thereof;

FIG. 4 is a side view thereof;

FIG. 5 is a bottom view thereof; and,

FIG. 6 is an enlarged detail cross-section view taken along line 6 of FIG. 2.
